[57] CLAIM

The ornamental design for an emergency sign for vehicles, as shown and described.

DESCRIPTION

In FIGS. 1, 2, 4, 5 and 6, the cord is shown broken away to indicate indeterminate length;

FIG. 1 is a front elevational view of the emergency sign for vehicles showing my new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.

The cord is fragmentarily shown for convenience of illustration.
